UNITED STATES PATENT OFFICE.

KARL M. HAMILTON, OF DAVENPORT, IOWA, ASSIGNEE, BY MESNE ASSIGNMENTS, TO
THE BETTENDORF COMPANY, OF BETTENDORF, IOWA, A CORPORATION OF IOWA.

UNDERFRAME FOR CARS.

1,097,800.

Specification of Letters Patent.

Patented May 26, 1914.

Application filed September 12, 1912. Serial No. 719,938.

To all whom it may concern:

Be it known that I, KARL M. HAMILTON, a citizen of the United States of America, and resident of Davenport, Iowa, have invented a certain new and useful Improvement in Underframes for Cars, of which the following is a specification.

This invention relates to metallic underframes commonly used in railway car construction, and particularly to that type of underframe sill in which the vertical height of the central portion thereof is greater than at the ends.

In an underframe designed to carry practically the entire load on a center sill made of commercial shapes such as I beams or channels, beams of great depth of section are employed. The depth of section is usually so great that to maintain M. C. B. standard measurements in connection with floor height, center plate height and coupler height, it becomes necessary to reduce the vertical height of that portion of the sill lying over the car trucks.

It is the usual custom when sills are made of I beams or channels to have same extend from bolster to bolster and complete the sill by securing draft sills thereto of less height or vertical dimension. The ends of the sill proper when secured to the draft sills would be reduced in vertical height by removing or displacing a portion of the web and bending the flanges toward one another, or by shearing off the lower flange and a tapering portion of the web at each end of the sill then reinforcing the sill by riveting angles along the severed edge. In sills of this type the reduced ends are usually terminated at the body bolsters of the underframe or allowed to extend past the bolster a short distance at which point they are secured to the draft arms or sills of the same height as the reduced end of the main sill.

The object of my invention is to effect this necessary reduction of height entirely in the draft arm portion of the sill, leaving the main or body portion of the sill in its original height throughout. This I accomplish as shown in the accompanying drawings in which—

Figure 1 is a plan view of a portion of an underframe showing the center sill consisting of two I beams, the channel draft arms, a portion of the body bolster and end sill. Fig. 2 is a side elevation partly in section of

the same portion of an underframe shown in Fig. 1. Fig. 3 is a detail cross section taken on line A—B of Fig. 2. Fig. 4 is a plan view of a portion of an underframe showing a modification of my invention as applied to a center sill made of a single I beam. Fig. 5 is a side elevation of Fig. 4. Fig. 6 is a detail cross section taken on line C—D of Fig. 5.

Similar numerals indicate similar parts throughout the several views.

While only a fragmentary view of an underframe is shown it is, of course, understood that the construction is identical at both ends of the car. The I beam center sill 1 (one end of which only is shown) terminates between the bolster 2 (one only being shown) at some little distance back therefrom, and is securely riveted to the rear ends of the rolled channel draft sill 3, which draft sills form a continuation of the center sill, extending on past the end sill 4 to which they are riveted, affording a support for the striking plate 5 and the coupler carrying-iron 6. To the inner face of the draft sills the draft gear stop members 7 are securely riveted. Passing through the web of the draft sills at about the center of their longitudinal length, through a suitable opening between the flanges thereof, is the body bolster 2. The rear ends of these draft sills 3 are bifurcated forming two prongs 8 and 9. These prongs are spread apart a distance approximately the vertical height of the center sill to which they are securely riveted. The shape of the upper prong of the bifurcation is left unchanged from its original form but the lower prong is bent downward at an angle for the greater portion of its length with that portion of its end contacting the center sill running parallel to the center sill flange and the upper prong.

When attaching the draft sills to a center sill made of two rolled members such as I beams illustrated in Figs. 1, 2 and 3, the lower outside flanges of the I beams may be coped or cut away where the ends of the draft sills lap the end of the center sills thus bringing the top and bottom surfaces of the widened portion of the draft sills and the center sill in the same plane. To insure the necessary strength the reinforcing plates 10 and 11 are riveted to the top and bottom flanges of the center sill and draft sills, and the plates 12 extending over the entire

bifurcated portion of the draft sills are riveted thereto and to the web of the center sills. When attaching the draft sills to a center sill consisting of a single I beam as shown in Figs. 4, 5 and 6, the rear bifurcated ends of the draft sills 3 are bent in toward, lap past and closely embrace the end of the center sill as shown at 13. Instead of coping or cutting away the lower flange 10 of the center sill where engaged by the draft sill, it may be left intact and the horizontal flanges of the draft sill prongs, which are normally at right angles to the web thereof, can be shaped to meet the contour of the 15 inner face of the center sill flange as shown at 14 and riveted thereto. To properly strengthen the sill at the juncture of the draft sills and center sill, the reinforcing plates 15 are extended over the entire bifurcated portion of the draft sills and riveted 20 to the web thereof and to the center sill end. This union is further strengthened by the filler plate 16 riveted between the reinforcing plates 15 and the web of the center 25 sill. Thus the draft sills with their rear ends widened to meet the vertical height of the center sill form, when joined thereto, a sill of fish belly shape such as are commonly used in car underframes. At the 30 present time it is the general practice to construct these sills by either taking a web sheet of sufficient length to extend from end sill to end sill of an underframe, shear it into fish belly form and rivet angles on both 35 sides of the web plate at the top and bottom edges; or as illustrated in U. S. Patent No. 620561, the ends of the beam are reduced in vertical dimensions by removing or displacing a portion of its web and bending the 40 lower flange toward the upper, bringing the severed edges of the web in contact, and when a beam of this kind is to be used in the center sill of an underframe, it is completed by riveting draft arms or sills to the 45 ends thereof of the same vertical dimension as the reduced ends of the beam; or as illustrated in U. S. Patent No. 776149, a channel or other rolled beam of sufficient length to extend from end sill to end sill would be 50 given the fish belly form by cutting the lower flange and a portion of the web from each end of the beam and riveting reinforcing angles to the severed edge. In my improved sill as described the fish belly form is 55 given it, not by reducing the ends of the deep central portion to meet the vertical height of the draft arms, but by maintaining the central portion in its original height throughout and effect the fish belly form by 60 increasing the vertical height of the adjacent ends of the draft arms to meet that of the central portion. It has also been the practice when draft arms were secured to the central portion of a sill to terminate the 65 central portion between the body bolsters or

at a point between the body bolster and end sill and either pass the body bolster through an opening in the central portion, or pass the sill through a bolster provided with a top and bottom plate, but

What I claim as new is—

1. In an underframe, the combination of metallic center sill members; of longitudinally extending metallic end members having bifurcated ends secured to said center sill members.

2. In an underframe, the combination of metallic center sill members; of end sills; of metallic end members having one end bifurcated and secured to said center sill member by said bifurcations and the other end secured to said end sills.

3. In an underframe, the combination of flanged beam center sills; of end sills; of flanged beam draft sills having one end bifurcated and secured to said center sills by said bifurcations and the other end secured to said end sills.

4. In an underframe, the combination of metallic center sill members; of end sills; of body bolsters; of draft sills connecting said center sills and end sills and provided with an opening between its upper and lower edges forward of the center sill members through which said bolsters pass.

5. In an underframe, the combination of metallic center sill members; of body bolsters; of longitudinally extending metallic end members having bifurcated ends secured to said center sill members and provided with an opening between their upper and lower edges through which said body bolsters pass.

6. In an underframe, the combination of metallic center sill members; of end sills; of body bolsters; of longitudinally extending end members having one end bifurcated and secured to said center sill member by said bifurcations and the other end secured to said end sill and provided with an opening between said bifurcations and end sill for the passage therethrough of said body bolster.

7. In an underframe, the combination of metallic center sill members, the vertical dimension of which is equal throughout their length; of longitudinally extending metallic draft sills, provided with draft gear stops, secured to the ends of said center sill members, the vertical dimension of said draft sills at their union with said center sills being greater than at their outer ends.

8. In an underframe, the combination of metallic center sill members, the upper and lower edges of which are parallel throughout their length; of longitudinally extending metallic draft sills secured to the ends of said center sill members and provided with draft gear stops, and bolster openings, the vertical dimension of said draft sills at

their union with said center sills being greater than at their outer ends.

9. In an underframe, the combination of metallic center sill members; of end sills; of longitudinally extending metallic draft sills having their rear ends bifurcated and secured to said center sill members, and their forward ends secured to and extended past said end sills and having a striking plate and draw bar carry-iron secured to the outer end thereof.

10. In an underframe, the combination of a single metallic center sill; of longitudinally extending metallic end members having bifurcated ends bent in toward and secured to said center sill.

11. In an underframe, the combination of a single flanged beam center sill of the same vertical dimension throughout its length; of end sills; of flanged beam draft sills having their forward ends spaced apart and secured to said end sill and their rear ends bent in toward and secured to said center sill, the vertical dimension of said draft arms being greater adjacent the center sill than at the end sill.

12. In an underframe, the combination of single flanged beam center sill; of body bolsters; of flanged beam draft sills having bifurcated ends bent in toward and secured to said center sill, and an opening between their top and bottom edges for the passage of said bolsters.

13. In an underframe, the combination of a single flanged beam center sill; of end sills; of flanged beam draft sills having their rear ends bifurcated and secured to said center sill, and their forward ends spaced apart and secured to and extended

past said end sill, and having a striking plate and coupler carry-iron secured to the outer end thereof.

14. In an underframe, the combination of a flanged beam center sill; of body bolsters; of longitudinally extending metallic draft sills secured to the ends of said center sill and provided with draft gear stops and openings between the top and bottom edges thereof forward of the center sill through which said bolsters pass.

15. A flanged beam sill of truss shape for car underframe consisting of a central portion of uniform vertical dimension throughout, flanged beam end portions secured to the central portion, the outer ends of which are of less vertical dimension than the central portion, and the inner ends of which are bifurcated and spread apart a distance approximating the vertical dimension of the central portion to which they are secured.

16. A truss shape metallic sill for car underframes consisting of a central portion of uniform depth of vertical section throughout; metallic end portions provided with bolster openings and draft gear stops, secured to the said central portion, the outer ends of said end portion being of less depth of vertical section than the said central portion, and the inner ends of which are increased in depth of vertical section substantially to that of the said central portion to which they are secured.

Signed by me at Beaver Dam, Wisconsin this 2nd day of September 1912.
